UNITED STATES PATENT OFFICE.

JOHN H. BROMLEY, OF PHILADELPHIA, PENNSYLVANIA.

DESIGN FOR A CARPET-PATTERN.

Specification forming part of Design No. 5,770, dated April 16, 1872.

To all whom it may concern:

Be it known that I, JOHN H. BROMLEY, of the city of Philadelphia, State of Pennsylvania, have invented a new and Improved Design for Carpets.

The nature of the design is fully set forth in the accompanying photographic illustration, to which reference is made.

What I claim as new, and desire to secure by Letters Patent, is—

The design for a carpet, substantially as shown.

JOHN H. BROMLEY.
